UNITED STATES PATENT OFFICE.

ROLLIN H. WHITE, OF CLEVELAND, OHIO, ASSIGNOR TO THE WHITE SEWING MACHINE COMPANY, OF CLEVELAND, OHIO, A CORPORATION OF OHIO.

CONDENSER MECHANISM FOR STEAM-CARRIAGES.

SPECIFICATION forming part of Letters Patent No. 740,207, dated September 29, 1903.

Application filed April 21, 1903. Serial No. 103,853. (No model.)

To all whom it may concern:

Be it known that I, ROLLIN H. WHITE, a citizen of the United States, residing at Cleveland, in the county of Cuyahoga and State of Ohio, have invented a certain new and useful Improvement in Condenser Mechanism for Steam-Carriages, of which the following is a full, clear, and exact description, reference being had to the accompanying drawings.

10 Steam-carriages as heretofore made have been most frequently criticised, because, first, they only carry a limited supply of water, and, second, they leave in their wake an objectionable cloud of steam.

15 The object of this invention is to cure both of the defects referred to by employing a novel condensing apparatus by which substantially all of the steam may be condensed and returned as water to the tank.

20 The invention consists in the construction and combination of parts hereinafter described, and pointed out definitely in the claims.

25 In the drawings, Figure 1 is a side elevation, partly in section, showing the condensing apparatus constituting my invention and the position it occupies relative to the carriage-body. Fig. 2 is a transverse substantially vertical section of the condenser, the 30 section being taken in the plane indicated by line 2 2 of Fig. 1. Fig. 3 is a longitudinal vertical section of one of the headers. Fig. 4 is a similar section of the other header, and Fig. 5 is a sectional plan view of the condenser.

35 The condenser is secured to the front of the carriage A, wherefore as the carriage moves forward it runs into the fresh air, by which it is cooled. It includes two headers B and C, 40 which occupy approximately vertical positions. These headers are connected by five, more or less, vertical rows of transverse and substantially horizontal pipes D D', upon which the metallic washers d may be secured 45 to increase the heat-radiating surfaces. One of these headers B is divided into two vertical chambers b b', located one behind the other, by the substantially vertical transverse partition b². Preferably three of the vertical

rows of horizontal pipes D' extend from the rear chamber b' to the header C, while two of said rows of pipes D connect the header C with the forward chamber b.

The exhaust side of the engine F is connected with the rear chamber b' by a pipe f. 55 The exhaust-steam therefore enters the chamber b', flows across into the header C through the pipes D', and thence back through the pipes D into the front chamber b. The rear rows of pipes D' are of course warmer than 60 the front rows, because they are only subjected to the cooling influence of air which has been somewhat warmed by its contact with the front rows of pipes. In passing through the rear rows of pipes the steam will 65 be cooled and some of it will be condensed. There will, however, be a greater degree of cooling, and consequently a greater degree of condensation, of the steam as it flows from the header C through the front rows of pipes 70 D back to the chamber b. Substantially all of the steam may be condensed in this condenser, and the water of condensation will all find its way to the bottom of the terminal condenser-chamber b. Connecting with the 75 bottom of this chamber is a discharge-pipe G, which is connected with a pump H, secured in a suitable position relative to the engine and adapted to be operated thereby.

K represents the water-tank, and J a filter, 80 into which preferably the water of condensation is forced through the pipe M by said pump. This filter may be a closed box, having near its lower end the transverse perforated partition j, and it should contain waste 85 or some other porous material which will prevent the oil, with which the water of condensation is mixed, from passing through it. The pipe M discharges into the upper end of this filter. A pipe N is connected with the lower 90 end of the filter below the perforated partition and extends up and discharges into the water-tank at a point near the top thereof. This pipe is so carried up to prevent as far as possible the flow of any oil from the filter 95 into the tank. The terminal condenser-chamber b has also connected with it, a little distance above its bottom, a pipe O, through

which any of the steam which is not condensed may escape and be delivered into the smoke-stack S.

Although in the construction shown the 5 condensed steam passes only twice across the front of the carriage—to wit, in one direction through the three rear vertical rows of pipes D and then back through the two front vertical rows of pipes D—it is obviously possible 10 to provide any desired number of series of transverse pipes and to so connect their ends that the steam must pass back and forth any number of times before it reaches the terminal chamber from which the water of condensation is pumped. For example, this result 15 might be attained with the construction shown by providing vertical partitions in both headers in planes indicated by the dotted lines b' and c in Fig. 5, which partitions, together with 20 the partition b², will divide the header B into three chambers and the header C into two chambers, which chambers are connected together in series by the transverse pipes. The steam entering the rear chamber of the header 25 B will in that event pass across through the rear vertical rows of transverse pipes into the rear chamber of the header C, thence back through the next vertical row of transverse pipes into the middle chamber of the header 30 30 B, thence through the next vertical row of transverse pipes into the front chamber of the header C, and then back through the two front vertical rows of transverse pipes into the terminal chamber of the condenser—to wit, the 35 front chamber b of the header B.

It sometimes happens that a forced draft through the stack is desirable, and this draft will be proportionate to the amount of exhaust-steam delivered into the stack. Means 40 are provided whereby substantially all or any part of the exhaust-steam may be delivered directly into the stack instead of the condenser.

A pipe R is connected with pipe f and discharges into the stack. In this pipe R is a 45 valve r, of any suitable construction, which may be closed and opened by means of an operating device T. When the valve is closed, the exhaust-steam follows the path heretofore 50 described to and through the condenser and the water of condensation is led back to the tank. When it is desired to have a forced draft in the stack, this valve is opened to a greater or less extent and the exhaust-steam 55 then passes directly into the stack.

The condenser-tubes are liable to become clogged up if means are not provided whereby they may be cleaned. With this end in view the outer sides b³c³ of both headers consist of removable plates secured normally in place by screws. By loosening these screws these end plates may be removed, thus permitting the cleaning of the tubes.

Having described my invention, I claim—

1. In a condenser, the combination of two 65 substantially parallel and approximately ver-

tical headers, a plurality of transverse pipes connecting said headers, one or more approximately vertical partitions in one or both of said headers dividing the same into approximately vertical chambers which are connected in series by said transverse pipes, a steam-inlet pipe connected to the first of the series of chambers, a discharge-pipe connected with the lower end of the terminal chamber, a 70 pump for drawing the water of condensation through said discharge-pipe and a discharge-pipe for the uncondensed steam connected with the terminal chamber and discharging into the smoke-stack. 75

2. In a condenser, the combination of two substantially parallel and approximately vertical headers, a plurality of transverse pipes connecting said headers, one or more approximately vertical partitions in one or both of 80 said headers dividing the same into approximately vertical chambers which are connected in series by said transverse pipes, a steam-inlet pipe connected to the first of the series of chambers, a discharge-pipe connected with the lower end of the terminal chamber, a 85 pump for drawing the water of condensation through said discharge-pipe, a discharge-pipe for the uncondensed steam connected with the terminal chamber and discharging into 90 the smoke-stack, a branch pipe connected with the steam-inlet pipe and also discharging into said stack, a valve in said branch pipe and means for opening said valve to any 95 desired extent whereby a greater or less proportion of the steam from the engine may be 100 conveyed to, and discharged directly into the stack to increase the draft, substantially as specified.

3. In a condenser, the combination of two 105 substantially parallel headers, a longitudinal partition within one of said headers dividing the same into two longitudinal chambers, a plurality of sets of transverse pipes connecting the rear chamber of the divided header 110 with the other header, fewer sets of transverse pipes connecting this same header and the front chamber in said first-mentioned header, a steam-inlet pipe connected to said first-mentioned chamber and a water-outlet 115 connected with said second-mentioned chamber and a pump for conveying away the water, substantially as described.

4. In a steam-automobile, the combination 120 of a carriage-body, a condenser consisting of two headers, one of said headers having a longitudinal partition dividing it into two longitudinal chambers, a plurality of sets of transverse pipes connecting the rear longitudinal chamber with the other header and 125 fewer sets of transverse pipes connecting this same header with the forward one of said longitudinal chambers, an engine, a pipe connecting the exhaust from said engine with said first-mentioned longitudinal chamber, a pump 130 operatively connected with the engine, a water-tank and a pipe through which said pump 135

may draw the water of condensation from said second-mentioned chamber and deliver it into said tank, substantially as described.

5. In a steam-automobile, the combination of a carriage-body, a condenser consisting of two headers, one of said headers having a longitudinal partition dividing it into two longitudinal chambers, a plurality of sets of transverse pipes connecting one of said longitudinal chambers with the other header, and fewer sets of transverse pipes connecting this same header with the other one of said longitudinal chambers, an engine, a pipe connecting the exhaust from said engine with said first-mentioned longitudinal chamber, a branch pipe connected with said exhaust-pipe and leading to the stack, a valve controlling the passage of the exhaust-steam through said branch pipe, and an exhaust-pipe leading from said condenser to the stack, substantially as described.
10. 6. In a steam-automobile, the combination of a carriage-body, a condenser consisting of two headers, one of said headers having a longitudinal partition dividing it into two longitudinal chambers, a plurality of sets of transverse pipes connecting the rear chamber with the other header, fewer sets of transverse pipes connecting this same header and the forward chamber in said first-mentioned header, a steam-inlet connected to said rear chamber, and means for conveying away the water of condensation, substantially as specified.
15. 7. In a condenser, the combination of two substantially parallel headers, a longitudinal partition within one of said headers, dividing the same into two longitudinal chambers, a plurality of sets of transverse pipes connecting the rear chamber with the other header, fewer sets of transverse pipes connecting this same header and the forward chamber in said first-mentioned header, a steam-inlet connected to said rear chamber, and means for conveying away the water of condensation, substantially as specified.

20. 8. In a condenser, the combination of two substantially parallel headers, a longitudinal partition within one of said headers, dividing the same into two longitudinal chambers, a plurality of sets of transverse pipes connecting the rear chamber with the other header, fewer sets of transverse pipes connecting this same header and the forward chamber in said first-mentioned header, a steam-inlet connected to said rear chamber, and means for conveying away the water of condensation, substantially as described.

25. 9. In a condenser, the combination of two substantially parallel headers, a longitudinal partition within one of said headers, dividing the same into two longitudinal chambers, a plurality of sets of transverse pipes connecting the rear chamber with the other header, fewer sets of transverse pipes connecting this same header and the forward chamber in said first-mentioned header, a steam-inlet connected to said rear chamber, and means for conveying away the water of condensation, substantially as specified.

In testimony whereof I hereunto affix my signature in the presence of two witnesses.
